UNITED STATES PATENT OFFICE

2,022,826

ELECTRIC CONTROL APPARATUS FOR
FUEL BURNERSAbraham L. Rubel, Des Moines, Iowa, assignor to
Penn Electric Switch Co., Des Moines, Iowa, a
corporation of Iowa

Application October 16, 1933, Serial No. 693,800

2 Claims. (Cl. 158—28)

An object of my present invention is to provide control apparatus for the electric circuit of a fuel burner, such apparatus being of simple construction and operable to automatically take care of various emergencies arising during the operation of the burner.

A further object is to provide an automatic controller including a combustion switch which is opened when combustion occurs in order to break the circuit through a lock-out switch so that upon combustion occurring the lock-out switch will not thereafter lock out.

Still a further object is to provide control apparatus including a room thermostat operated relay which normally initiates and terminates operation of a fuel burner and which initiates operation of ignition mechanism for the fuel burner, termination of the operation of the ignition mechanism being effected by an ignition trip mechanism which in turn is operated by a combustion switch, the combustion switch including a lost motion connection to delay the operation of the ignition trip mechanism.

A further object is to provide control apparatus including a combustion switch having a friction connection for one of the movable contacts and a lost motion connection which provide for de-energizing the relay and re-cycling by re-establishing the starting circuit, respectively, so that between relay de-energization and re-cycling a purging period is provided, thus allowing the combustion chamber of a furnace or the like to be cleared of dangerous gases by the natural draft therein before the ignition mechanism is re-energized by establishment of the starting circuit and thus eliminating an explosion upon such re-energization.

Another object is to provide a control structure in which ignition contacts are normally closed, but the ignition current does not flow through them until a room thermostat is also closed, these contacts being so mounted on a relay that they remain closed when the relay is energized and ignition trip mechanism being provided for thereafter opening them, a combustion switch being utilized to operate the ignition trip mechanism and having inherent means for delaying such operation for a time period after the combustion chamber of the furnace begins to heat up, such delay being especially desirable for the rotary types of oil burners requiring a long ignition period for insuring combustion.

Still a further object is to provide control apparatus in which a relay is de-energized by con-

tacts of a combustion switch which have the peculiarity of closing only after the combustion switch moves from cold to hot position and then starts to return toward cold position, such peculiarity being effected by a frictional mounting 5 for one of the contacts of the switch.

With these and other objects in view my invention consists in the construction, arrangement and combination of the various parts of my device, whereby the objects contemplated are 10 attained, as hereinafter more fully set forth, pointed out in my claims, and illustrated in the accompanying drawing, in which:

Figure 1 is an electrical diagrammatic view of an electric control apparatus for fuel burners 15 embodying my invention.

Figure 2 is a simplified wiring diagram of the same.

Figure 3 illustrates different successive positions of a combustion switch shown in Figure 1. 20

Figures 4 and 5 are different successive views of the relay switch shown in Figure 1 during its operation.

Figure 6 is a sectional view on the line 6—6 of Figure 1 showing details of a combustion switch 25 which I employ; and

Figure 7 is a front view of the ratchet and lost motion mechanism of the combustion switch.

On the accompanying drawing, a plurality of contacts are illustrated. Lock-out switch contacts are shown at 10. A relay switch has motor contacts 12 and 14, ignition contacts 16 and holding contacts 18. The relay switch includes an ignition trip mechanism having contacts 20. A combustion switch is provided with ignition 35 trip contacts 22, relay de-energizing contacts 24 and starting contacts 26.

The lock-out switch also includes a cam 28 spring actuated to separate the normally closed contacts 10 but normally held from doing so by a bimetal latch 30. The latch 30 is adapted to be warped to unlatched position by a lock-out switch heater 32 when it is hot.

The relay switch includes a relay coil 34 divided into two separate coils 34a and 34b by a 45 central connection. An armature 36 normally held spaced from the coil 34 is adapted to be attracted thereby when the coil is energized. A bridge piece 38 carried by the armature 36 connects one of the contacts 12 with one of the 50 contacts 14, when the relay is energized as in Figure 4, thereby eliminating a pig-tail connection.

An extension 40 on a leaf spring 42 of the relay switch is adapted to be engaged by the bridge piece 38 during opening of the relay arma-

ture 36 to the position of Figure 1. The leaf spring 42 carries one of the contacts 16.

An ignition trip mechanism is provided in the relay switch and includes contacts 20 and 20a. 5 The contact 20a serves as an armature for an electromagnet 44.

The contact 20a retains the contacts 16 engaged as in Figures 1 and 4 whether the relay is or is not energized providing the electromagnet 44 is 10 not energized and permits them to separate providing the relay is energized and the magnet is then energized.

The combustion switch includes a rotatable rod 46 and a bimetal coil 48 responsible to temperature in the combustion chamber of a furnace. One end of the coil 48 is secured to the rod 46 as at 47 and the other end is stationarily anchored as at 49 to a housing 51 for the combustion switch. The combustion switch also includes a toothed disk 52 and a lost motion connection between the rod 46 and the toothed disk comprising an arm 50 on the rod and spaced stops 54 on the disk. The disk 52 is rotatably mounted on the rod 46. A leaf spring 56 carrying one of the contacts 26 20 is adapted to coact with the periphery of the toothed disk 52 to be operated thereby during rotation thereof such cooperation being shown in Figure 7; the free end of the spring 56 tends to remain in the position of Figure 3 (A) and the 25 full line position of Figure 7 so that, due to its path of movement describing an arc 53, it can be swung immediately upon the toothed disk beginning to rotate and after a predetermined degree of rotation permits the teeth thereof to 30 slip past it as in Figure 1 and Figure 3 (C).

The combustion switch further includes a frictional mounting comprising a plate 58 for one of the contacts 24, the arm carrying this contact and also the arm carrying the upper contact 22 40 being actuated from the leaf spring 56. All of the arms carrying the contacts 22, 24 and 26 are leaf springs except the one carrying the upper contact 24 and having the plate 58 which can be of rigid material and pivoted at 61. The plate 58 is caused to frictionally engage the insulating block 55 which indirectly supports the contacts 22, 24 and 26 by means of a spring washer 59 on the pivot 61.

A transformer 60 is provided for furnishing 50 current for the relay coil 34, the lock-out switch heater 32 and the ignition trip magnet 44.

Terminals L and L' for line wires, I for ignition mechanism, M for motor and R and R' for a room thermostat or main control switch, are 55 illustrated in Figure 1. These are also illustrated in Figure 2 and a motor, ignition mechanism and a room thermostat are indicated as "Motor", "Ign." and "Room therm.", respectively. The primary and secondary of the transformer 60 60 are indicated at "Pri." and "Sec.".

Practical operation

The circuit connections with the various coils, heaters, contacts, etc., are all fully shown in Figures 1 and 2. The parts in Figure 1 and the contacts in Figure 2 are in normal or non-operating position.

Starting circuit

70 When the room thermostat closes because of lowering of the room temperature to a predetermined degree, a starting circuit is closed from the terminal R' through the room thermostat, the terminal R, the lock-out switch heater 32, the relay coil 34a and the normally closed start-

ing contacts 26 of the combustion switch to the upper end of the transformer secondary.

This causes the armature 36 to be attracted whereupon its contacts 12, 14 and 18 are closed and 16 are held closed or in their normal position 5 by the ignition trip armature 20a as shown in Figure 5.

The closing of the contacts 12 and 14 establishes both the motor circuit and the ignition circuit from the terminal L through the lock-out 10 switch contacts 10, the contacts 12 and 14 and the contacts 16 which are already closed. Closing of the holding contacts 18 provides a holding circuit for the relay which is energized under certain circuit conditions. 15

Running circuit

If combustion occurs, the starting contacts 26 will first be opened by reason of the bimetal coil 48 slightly rotating the toothed disk 52, as shown 20 in Figure 3 at A. This breaks the starting circuit, but permits the current from the upper end of the relay coil 34a to flow through the coil 34b and the holding contacts 18, thus holding the relay in its energized position. Passage of the 25 current through the coil 34b, instead of the shunt circuit including the contacts 26, reduces the current so that the lock-out switch heater 32 will not become hot enough to trip the lock-out switch to open circuit position. 30

If combustion does not occur, then the secondary current from the transformer 60 will be of higher value because it is choked only by the coil 34a and not by the coils 34a and 34b so that the heater 32 will heat up sufficiently to trip the 35 lock-out switch.

If combustion does occur, the running circuit just described will normally be maintained until the room thermostat opens it because of a rise of the temperature in the room to a predetermined degree. 40

Ignition trip circuit

This circuit may be traced from the terminal R through the ignition trip de-energizing contacts 20 and 20a, the magnet 44 and the ignition trip contacts 22 of the combustion switch when they close. It is desirable to have them close after a delayed period of time however. Accordingly, the spring arm 56, due to its tendency 50 to assume a substantially central position will move the toothed disk 52 to the position of Figure 3 at A after the arm 50 of the combustion switch moves from cold toward hot position, the left stop pin 54 following it by reason of the arm 55 56 rotating the toothed disk 52 until the position at A is assumed, whereupon the arm 50 will move from the left stop pin to the right one. After it engages the right one, as at B, both contacts 24 will be moved downwardly but will not become 60 engaged.

Finally, the contacts 22 will become engaged, whereupon energizing the ignition trip magnet 44 and attracting the armature 20a. This will permit the spring arm 42 of the relay switch to 65 spring upwardly from the position of Figure 4 to the position of Figure 5, the contacts 20 and 20a during this operation becoming separated so that after ignition trip occurs, current will no longer flow through the ignition trip circuit. 70

Failure of combustion after establishment

After combustion has once been established, if it should fail for any reason, the combustion switch will move from the hot position of Fig- 75

ure 3 at C back through the positions D, E, F and G to the cold position of Figure 1.

In the D position, the arm 58 has moved counter-clockwise and the spring 56 has caused the right stop pin 54 to follow it, first separating the ignition trip contacts 22 so that they are in initial position. Further movement, as at E, will permit the spring 56 to allow the lower contact 24 to contact with the upper one, thus establishing a relay de-energizing circuit by reason of the contacts 24 shunting the relay coil 34. This opens the motor contacts 12 and 14, thus de-energizing the motor and the ignition mechanism and opens the holding contacts 18, thus placing them all in position as for initial operation.

When the armature 36 of the relay switch moves to its initial position, the bridge piece 38 engages the arm 40 of the leaf spring 42, pulling it from the position of Figure 5 to the position of Figure 1, thereby permitting the armature 26a to assume its position of Figure 1 to hold the contacts 16 engaged when the relay is again energized as in Figure 4.

The combustion switch then moves to the position of F in Figure 3, the arm 58 swinging from the right hand stop pin 54 toward the left one to provide a time period in which purging can occur. Finally the contacts 24 will be opened, as at G, and then the contacts 26 will be closed as in Figure 1. Upon such closing of the contacts 26, the controller re-initiates the starting circuit, thus re-cycling the burner. The burner will recycle two or three times if it cannot operate properly after one purging period, whereupon the successive heatings of the lock-out switch heater 32 will be sufficient to trip the lock-out switch. The trouble must then be remedied and the lock-out switch manually reset.

The combination of toothed disk or slip connection in the combustion switch with the lost motion connection, the spring arm 56 which tends to hold the ratchet in the central position of Figure 3 at A and E and the friction connection at 58 all obviously enter into the proper operation of the controller, as hereinbefore described to provide an extended ignition period and a purging period.

Some changes may be made in the construction and arrangement of the parts of my device with-

out departing from the real spirit and purpose of my invention, and it is my intention to cover by my claims, any modified forms of structure or use of mechanical equivalents which may be reasonably included within their scope.

I claim as my invention:

1. A control system for a fuel burner having a motor controlled fuel feeding means and ignition mechanism comprising in circuit, a main control switch, a first relay having contacts controlling the motor circuit and a holding circuit for said relay which are closed only when the relay is energized and ignition contacts which are closed when the relay is de-energized, a second relay controlling trip mechanism which when energized permits said ignition contacts to open and a combustion responsive switching mechanism having first contacts controlling energization of said first relay which are closed in the absence of combustion and open immediately after combustion is obtained, second contacts controlling energization of said second relay which are closed in the presence of combustion and which open immediately upon cessation of combustion and third contacts which close and remain closed for a time period subsequent to the opening of the second contacts and then open prior to the reclosing of the first contacts, said third contacts, when closed, effectuating deenergization of said first relay.

2. A control system for a fuel burner having a motor controlled fuel feeding means and ignition mechanism comprising in circuit, a main control switch, a first relay having contacts controlling the motor circuit which are closed only when the relay is energized and ignition contacts which are closed when the relay is de-energized, a second relay controlling trip mechanism which when energized permits said ignition contacts to open and a combustion responsive switching mechanism having first contacts controlling energization of said first relay which are closed in the absence of combustion and open immediately after combustion is obtained and second contacts controlling energization of said second relay which are closed in the presence of combustion and which open immediately upon cessation of combustion.
